GOLF PUTTER HEAD

Erl A. Koenig, Poestenkill Road,
Troy, N.Y. 12180

Filed May 7, 1968, Ser. No. 11,807

Term of patent 14 years

U.S. Cl. D34—5
Int. Cl. D21—03

FIG. 1

FIG. 2

FIG. 3

FIG. 4

FIG. 6

FIG. 5

I claim:

The ornamental design for a golf putter head, substantially as shown.
